UNITED STATES PATENT OFFICE

112,336

DESIGN FOR A CHARACTER DOLL OR SIMILAR ARTICLE

Andrew T. Cahill, Des Moines, Iowa

Application August 17, 1938, Serial No. 79,405

Term of patent 7 years

To all whom it may concern:

Be it known that I, Andrew T. Cahill, a citizen of the United States and a resident of Des Moines, in the county of Polk and State of Iowa, have invented a new, original, and ornamental Design for a Character Doll or Similar Article, of which the following is a specification, reference being had to the accompanying drawing, forming part thereof.

I claim:

The ornamental design for a character doll or similar article, substantially as shown.

ANDREW T. CAHILL.
